US0D1015346S

(12) **United States Design Patent** (10) Patent No.: **US D1,015,346 S**
(45) Date of Patent: ** Feb. 20, 2024

(54) **DISPLAY SCREEN OF A COMPUTING DEVICE WITH A GRAPHICAL USER INTERFACE**

(71) Applicant: **GoPro, Inc.**, San Mateo, CA (US)

(72) Inventors: **Evan Kosowski**, San Diego, CA (US); **Joshua Hamill**, Poway, CA (US); **Nicholas Woodman**, Big Sky, MT (US); **Christopher James Frost**, Rancho Santa Fe, CA (US); **Otto Sievert**, Oceanside, CA (US)

(73) Assignee: **GoPro, Inc.**, San Mateo, CA (US)

(**) Term: **15 Years**

(21) Appl. No.: **29/825,812**

(22) Filed: **Feb. 4, 2022**

(57) **CLAIM**

The ornamental design for a display screen of a computing device with a graphical user interface, as shown and described.

DESCRIPTION

FIG. 1 is a view of a display screen of a computing device with a graphical user interface; and, FIG. 2 is a view of a display screen of a computing device with a graphical user interface.

The broken lines showing the display screen form no part of the claimed design. The other broken lines in the figures show portions of the graphical user interface that form no part of the claimed design.

1 Claim, 2 Drawing Sheets
